CLAIM

Related U.S. Application Data

The ornamental design of an element of an all terrain vehicle, as shown and described.

(62) Division of application No. 29/127,281, filed on Aug. 4, 2000.

DESCRIPTION

(51) **LOC (7) Cl.** **12-11**
(52) **U.S. Cl.** **D12/107; D12/114**
(58) **Field of Search** D12/107, 1, 3,
D12/114; 180/225, 229, 233, 311, 312,
315

FIG. 1 is a top plan view of an element of an all terrain vehicle showing our new design;

FIG. 2 is a left side view thereof, with the right side view being a mirror image thereof; and,

FIG. 3 is a front view thereof.

The rear view is omitted since it has no intended use.
